REFRIGERATOR CABINET

Orland H. Yoxximer, Springfield, Mass., assignor
to Westinghouse Electric & Manufacturing
Company, East Pittsburgh, Pa., a corporation
of Pennsylvania

Application December 31, 1940, Serial No. 372,608

1 Claim. (Cl. 20—35)

This invention relates to refrigerator cabinet construction and more especially to the construction of the cabinet and door adjacent the door seal.

One object of the invention is to provide such construction having a low heat leakage.

Another object of the invention is to provide a deeply-resilient door-sealing gasket in combination with a narrow heat leakage path of air between the door and the cabinet wall.

A further object is to provide a refrigerator door of strong construction.

These and other objects are effected by my invention as will be apparent from the following description and claim taken in connection with the accompanying drawing, forming a part of this application, in which:

Fig. 1 is an elevation of a domestic refrigerator embodying the invention;

Fig. 2 is a horizontal sectional view of the refrigerator of Fig. 1 with the door closed; and

Fig. 3 is a view in perspective of the sealing gasket for the door.

Referring specifically to the drawing for a detailed description of the invention, the reference numeral 10 represents a refrigerator cabinet comprising an outer shell 11 having a vertically-extending substantially rectangular access opening 12 in its upper portion. An inner liner 13 defines a food storage compartment 9 and is secured in the cabinet by means of a breaker strip 14 and sheet metal screws 15 and by internal supports, not shown in the drawing. The edges 16 of the sides and the top of the outer shell 11 are turned inwardly around the access opening 12 and the edges 17 of the inner liner 13 are turned outwardly to provide attachment flanges for the breaker strip 14. Heat insulating material 18 is packed between the inner liner 13 and the outer shell 11.

An evaporative cooling unit 20 is disposed in the upper portion of the food storage compartment 9 to cool the same. The cooling unit 20 also induces a vertical circulation of air therein which is down the back, across the bottom, and up the front of the food liner 13. The breaker strip 14 comprises four panels or strips 19 of heat insulating material. The strips 19 are non-metallic and non-hygroscopic and are preferably formed of a material impregnated with a resinous condensation product, such as the product known by the trade-mark "Micarta." All of the strips 19 lie in the same vertical plane and form a portion of the front wall of the cabinet. The 55

meeting edges of the strips 19 are mitered and are concealed by corner clips 21.

A frameless door 23 is secured to the cabinet by hinges 24 and comprises an inner panel 25 consisting of a sheet of stiff, molded, moisture-proof heat insulating material and an outer dished sheet of metal 26, the edges 27 of which are turned inwardly and are secured to the inner panel 25 peripherally thereof by screws 28, as shown in Fig. 2. The inner panel 25 is preferably formed of a material such as that used for the breaker strips 19. It has been found that a thickness of between $\frac{1}{8}$ and $\frac{3}{16}$ of an inch of the product known by the trade-mark "Micarta," for example, provides a door which is extremely light and sufficiently strong. The light inner panel 25, together with the lack of a frame in the door, reduces the heat leakage through the door and the inertia developed by the door when it is slammed shut. Non-rigid heat insulating material 33 is preferably disposed between the inner door panel 25 and the outer dished sheet 26.

A rubber sealing gasket 34 of substantially e section is secured to the edge of the door with the base 35 of the e clamped between the inner panel 25 and the edges 27 of the dished sheet 26 of the door 23 and held in place by the sheet metal screws 28. The head or balloon 36 of the e sectioned gasket 34 overlies the heads of the sheet metal screws 28 and when the door 23 is closed, the balloon 36 of the sealing gasket 34 lies near the outer margin of the breaker strips 19.

The inner panel 25 is molded to provide a bulge or offset 37 adjacent to and extending toward the breaker strips 19, which bulge reduces the air space 38 between the breaker strips 19 and the door 23. The correct proportioning of this air space 38 is important, for if too wide, an abnormally large amount of heat will leak into the cabinet 10 through this air space 38, and if too narrow, moisture will condense on the breaker strips 19. The reason for this is as follows: If the air space 38 is too wide, the air in the space 38 will be circulated actively together with the air in the food compartment 9, which circulation is generally upward along the door 23. Cold air from the interior of the food compartment 9 will, therefore, circulate adjacent to the rubber sealing gasket 34. Since rubber is a relatively poor heat insulator the circulating air will absorb heat from the warm air surrounding the refrigerator cabinet 10. If the air space 38 is too narrow, warm, moist air from the exterior of the cabinet 10 will be trapped in the air space 38 whenever

the door 23 is closed. This air will gradually cool while in the air space 38 and the moisture contained in the air will condense on the heat breaker strips 19.

The offset portion 37 of the inner panel 25 adjacent the breaker strips 19 also permits the use of a rubber sealing gasket 34 with a large balloon 36. A sealing gasket having a large balloon 36 decreases the heat leakage across the gasket because of the greater air space in the balloon 36. It also affords greater resiliency, so that the gasket 34 can conform to irregularities in the fitting of the door 23, thus permitting greater tolerances in manufacture.

The central portion 39 of the inner panel 25 is dished inwardly. The configuration of the panel 25 both at its edges 37 and at its center adds to its strength. The inner panel 25 tends to warp because the material is subject to different conditions of moisture and temperature on its two sides. The outer surface is exposed to the cold, dry air in the cabinet while the inner surface of the panel 25 is exposed to warmer air within the door. The panel, furthermore, has a tendency to warp even though the air conditions at its two sides are the same, because its inner and outer surfaces may be finished with different materials. The tendency of the panel 25 to warp is materially decreased by the shoulder portion adjacent its margin and the dished center portion and this decreased tendency of warping adds to its strength and facilitates assembling the door.

It will be apparent from the above that this invention provides a refrigerator cabinet having a low heat leakage, that it affords the use of a large balloon sealing gasket in combination with a narrow heat leakage path of dead air between

the cabinet wall and the door, and that it provides a door of unusually strong construction.

While I have shown my invention in but one form, it will be obvious to those skilled in the art that it is not so limited, but is susceptible of various changes and modifications without departing from the spirit thereof, and I desire, therefore, that only such limitations shall be placed thereupon as are specifically set forth in the appended claim.

What I claim is:

In a refrigerator cabinet, the combination of a cabinet structure having an access opening; heat breaker strips disposed around said opening, said heat breaker strips having the major portion of their exposed surfaces lying in one plane and surrounding said opening; and a door for said opening, said door comprising an outer arched panel, an inner panel of rigid heat-insulating material secured at its edges to the edges of said outer panel, and nonrigid heat-insulating material between said panels, said door overlying said exposed major portion of the breaker strips; and a sealing gasket between the cabinet and the periphery of said door, said inner panel having portions adjacent the sealing gasket lying in substantially one plane, said inner panel also having portions facing said major portions of the breaker strips which portions of the inner panel are offset toward said breaker strips from the plane of the portions of the panel adjacent said sealing gaskets to decrease the air gap between said inner panel and said portions of the breaker strips and to add rigidity to said inner panel, said offset portion of the inner panel being of substantially the same thickness as said portion adjacent the sealing gasket.
